United States Patent

Des. 241,563
Patented Sept. 21, 1976

241,563

GOLF CLUB HEAD

Jimmy C. McCord, Rte. 4, Box 20,
Roanoke, Ala. 36274

Filed Sept. 5, 1975, Ser. No. 610,551

Term of patent 14 years

Int. Cl. D21—02

U.S. Cl. D34—5 GH

FIG. 1 is a perspective view of a golf club head showing my new design;

FIG. 2 is a front elevational view;

FIG. 3 is a side elevational view as seen from the left side of FIG. 2;

FIG. 4 is a rear elevational view;

FIG. 5 is a side elevational view as seen from the right side of FIG. 2;

FIG. 6 is a top plan view; and

FIG. 7 is a bottom plan view.

I claim:

The ornamental design for a golf club head, as shown and described.
